(57) **CLAIM**

The ornamental design for an ultrasound machine, as shown and described.

DESCRIPTION

FIG. 1 is a top, left, front perspective view of an ultrasound machine showing the new design;

FIG. 2 is a front view of the invention illustrated in FIG. 1; FIG. 3 is a right side view of the invention illustrated in FIG. 1;

FIG. 4 is a rear view of the invention illustrated in FIG. 1; FIG. 5 is a left side view of the invention illustrated in FIG. 1;

FIG. 6 is a bottom view of the invention illustrated in FIG. 1;

FIG. 7 is a top view of the invention illustrated in FIG. 1; and,

FIG. 8 is a bottom, left, front perspective view of the invention illustrated in FIG. 1.

The broken lines in the drawings depict portions of the ultrasound machine that form no part of the claimed design.

1 Claim, 8 Drawing Sheets
